(57) CLAIM

The ornamental design for a textile with camouflage pattern, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a top plan view of textile with camouflage pattern, showing our new design.

The broken lines surrounding the FIGURE depict the boundaries of the claim and form no part thereof.
